(57) **CLAIM**

The ornamental design for the food storage container lid, as shown and described.

DESCRIPTION

FIG. 1 is a front perspective view of the food storage container lid;

FIG. 2 is a front view thereof;

FIG. 3 is a rear view thereof;

FIG. 4 is left side view thereof;

FIG. 5 is a right side view thereof;

FIG. 6 is a top view thereof;

FIG. 7 is a bottom view thereof;

FIG. 8 is a front perspective exploded view illustrating the food storage container lid as it fits on a food storage container base; and,

FIG. 9 is a front perspective exploded view illustrating the food storage container lid as it fits on a second food storage container base.

The broken lines depict portions of the food storage container lid that form no part of the claimed design.
